BICYCLE LOCK

Andrew Y. Bleier, Chicago, Philip J. Burnstein, Skokie, and John J. Aiken, Bolingbrook, Ill., assignors to Bik-Lok, Inc., Chicago, Ill.

Filed Apr. 25, 1975, Ser. No. 571,801

Term of patent 14 years

Int. Cl. D8—07

U.S. Cl. D8—113

FIG. 1 is a left side elevational view of a bicycle lock, showing our new design;

FIG. 2 is a rear elevational view thereof;

FIG. 3 is a right side elevational view thereof;

FIG. 4 is a front elevational view thereof;

FIG. 5 is a bottom plan view thereof; and

FIG. 6 is a top plan view thereof.

We claim:

The ornamental design for a bicycle lock, substantially as shown.
